UNITED STATES PATENT OFFICE

155,628

DESIGN FOR A WATCHCASE

Harry Reinstein, Rye, N. Y.

Application April 12, 1949, Serial No. 1,919

Term of patent 3½ years

(Cl. D42—8)

To all whom it may concern:

Be it known that I, Harry Reinstein, a citizen of the United States of America, residing in Rye, county of Westchester, and State of New York, have invented a new, original, and ornamental Design for a Watchcase, of which the following is a specification, reference being had to the accompanying drawing, forming part thereof, wherein,

Figure 1 is a face view of a watchcase showing my new design.

Figure 2 is a side elevational view; and

Figure 3 is an end elevational view.

The opposite side of the watchcase shown in Figure 1 is substantially plain in appearance.

I claim:

The ornamental design for a watchcase, substantially as shown and described.

HARRY REINSTEIN.
